United States Patent Office

Des. 188,512
Patented Aug. 2, 1960

188,512

BASKET

Roger F. Haag, Abingdon, Md.

Filed July 2, 1957, Ser. No. 46,819

Term of patent 14 years

(Cl. D58—4)

FIG. 1

FIG. 2

FIG. 3

FIG. 4

Fig. 1 is a top perspective of a basket, showing my new design;

Fig. 2 is an end elevation thereof;

Fig. 3 is a top plan thereof; and

Fig. 4 is a side elevation.

I claim:

The ornamental design for a basket, as shown.
